AUTOMATIC IGNITION AND CONTROL
MECHANISM FOR OVEN BURNERS

Richard L. Perl, Galion, and John M. Hoff, Mansfield, Ohio, assignors to The Tappan Stove Company, Mansfield, Ohio, a corporation of Ohio

Application December 10, 1951, Serial No. 260,902

10-Claims. (Cl. 161—9)

1

This invention relates to an automatic electric ignition and control mechanism for cooking range burners using gaseous fuel and is a modification of the control mechanism shown in the co-pending application of Charles M. Mayer and John M. Hoff filed April 3, 1950, Serial No. 153,664, now Patent No. 2,577,787. It is especially designed and adapted for automatically igniting and controlling the operation of oven burners in cooking ranges, and may be used in conjunction with a time control mechanism or independently thereof as desired.

The mechanism is designed for use with a main gaseous fuel burner which is adapted to be ignited by a gaseous fuel pilot burner. As long as the pilot burner is ignited it is immaterial whether or not the main burner burns constantly. It may be extinguished for some reason, but it will be promptly re-ignited by the pilot burner if fuel is supplied thereto. But if the pilot burner is extinguished for any reason while the main control valve is still open to supply gas to the main burner a very dangerous situation sometimes arises. Let us assume that both the pilot burner and the main burner are extinguished during operation for some reason. Gas can then flow to the main burner but since the pilot burner is extinguished the main burner will not be ignited and unburned gas will accumulate in the oven which may violently explode when an attempt is made to ignite either the main or pilot burner. It has been found by experience that both the pilot burner and the main burner are frequently extinguished during use while the main control valve is open to supply gas to the main burner. This is sometimes due to a momentary failure of the gas supply or the slamming of the oven door or to various other reasons.

In order to prevent any accumulation of unburned gas and thus eliminate any danger of an explosion therefrom in the event the pilot burner is extinguished for any reason while the control valve is still set to supply gas to the main burner, we provide in our improved apparatus safety control mechanism by which the supply of gas to both the main burner and the pilot burner is completely cut off, independently of the main control valve, in the event the pilot burner is extinguished for any reason while the main gas control valve is open.

Our improved apparatus includes a main gaseous fuel burner by which the oven in a cooking range is heated. The main burner is adapted to be ignited by a gaseous fuel pilot burner which burns only during the time the oven is in operation. At other times the supply of gas to both the main burner and the pilot burner is cut off

2

by a main control valve and a safety control valve mechanism which are interposed in a conduit between the gas supply manifold and the burners. When the main control valve is open gas will flow from the manifold into a safety control valve mechanism. From the safety control valve mechanism gas will flow through a small branch conduit directly to the pilot burner; and through the main conduit, the main control valve and a standard thermostatically operated oven temperature control valve to the main burner. A normally open master control switch which is operatively associated with the main control valve is arranged to be closed by the opening of the main control valve and to be opened by the closing of the main control valve. The closing of the master control switch, as the main control valve is opened to supply gas to the main burner, energizes through a normally closed thermostatically operated switch, an electric resistance ignition element and a solenoid which is operatively connected to the safety control valve mechanism. The energization of the solenoid causes it to operate the safety control valve mechanism to permit the flow of gas to the pilot burner while cutting off the supply of gas to the main burner. The pilot burner is ignited by the electric ignition element and projects a flame against a thermostatic element, which controls the operation of the normally closed switch, and against a thermocouple which is operatively connected to the safety control valve mechanism. After the thermostatic element becomes heated it opens the normally closed switch which de-energizes the electric ignition element and the solenoid. As soon as the solenoid is de-energized the safety control mechanism is automatically operated by spring means to supply gas to the main burner through the main control valve and the oven temperature control valve. The main burner is then ignited by the pilot burner. The thermocouple, as long as it is heated by the pilot burner maintains the safety control valve mechanism in condition to supply gas to both the main burner and the pilot burner. The oven temperature control valve then regulates the supply of gas to the main burner so as to maintain the desired oven temperature. As long as the pilot burner is ignited the main burner will burn normally under the control of the oven temperature control valve until the main control valve is manually turned off. But if during operation the pilot burner is extinguished for any reason the thermocouple will immediately cool and allow the safety control valve mechanism to automatically cut off the supply of gas to both the main burner and the pilot burner. As an

example of the manner of operation of the apparatus, let us assume that during operation the pilot burner is suddenly extinguished, for instance, by a momentary failure of the gas supply from the manifold to the burners. The thermocouple immediately cools, allowing the safety control valve mechanism to cut off communication between the manifold and both the main burner and the pilot burner. The main control valve is still open and the master switch closed. Then after the thermostatic element has cooled, closing the normally closed switch, which is maintained open by the thermostatic element during normal operation of the oven, the electric ignition element and the solenoid are again energized. The energization of the solenoid will cause it to operate the safety control valve mechanism to establish communication between the manifold and the pilot burner only. Then when gas is again available the pilot burner will be ignited and re-establish normal operation of the oven as previously described. In the event of a power failure during normal operation of the oven, the main burner will continue to operate normally under the control of the oven temperature regulator valve until the burner is turned off by the main control valve, assuming of course that the pilot burner continues to burn. In the event of a power failure before gas is turned on by the main control valve, the pilot burner can be manually ignited as will be hereinafter explained. The supply of gas to both the main burner and the pilot burner will then be controlled by the pilot burner through the thermocouple and safety control valve mechanism as previously described.

In order to extinguish the pilot burner when the operation of the main burner is terminated by the closing of the main control valve, we provide an interrupter switch in the circuit between the thermocouple and the safety control valve mechanism. This switch is located in the same casing as the master control switch and is opened and closed by the closing and opening of the main control valve simultaneously with the opening and closing of the master control switch. Then when the manually operable main control valve is closed to cut off the supply of gas to the main burner, the interrupter switch is simultaneously opened, breaking the circuit between the thermocouple and the safety control valve mechanism which permits the safety control valve mechanism to cut off the supply of gas to both the pilot burner and the main burner.

When it is desired to use the apparatus in conjunction with any standard time control mechanism, we provide a supplemental master switch and a supplemental interrupter switch which are simultaneously opened and closed at predetermined times by the time control mechanism. The supplemental master switch is inserted in the main circuit controlled by the primary master switch, and the supplemental interrupter switch is inserted in the thermocouple circuit controlled by the primary interrupter switch. In use the time control mechanism is set to initiate operation of the oven burner at a predetermined time and to terminate operation thereof at a predetermined later time, after the main control valve has been turned on for automatic operation which closes the primary master switch and the primary interrupter switch. Then when the supplemental switches which are now in series with the primary switches are closed by the time con-

trol mechanism the apparatus will function in the same manner as previously described.

During a prolonged power failure one may desire to use the oven several different times. In order to eliminate the necessity of either keeping the burner operating constantly during a prolonged power failure or manually setting the safety control valve mechanism and lighting the pilot burner with a match each time it is desired to use the oven, we provide means whereby the pilot burner will burn constantly and will not be extinguished each time the main burner is turned off by the closing of the main control valve. In this case the circuit between the thermocouple and the safety control valve mechanism will not be broken when the main control valve is turned off to stop operation of the main burner, so that the safety control valve mechanism will remain in condition to always admit gas to the pilot burner and to the main burner whenever the main control valve is opened. If under this condition the pilot burner is extinguished for any reason the thermocouple will cool and the safety control valve mechanism will then cut off the supply of gas to both the main burner and the pilot burner.

The principal object of the invention is to provide an improved electrical ignition and automatic control system for cooking range oven burners using gaseous fuel.

Another object of the invention is to provide in an electrical ignition and control system of the character described improved means for completely shutting off the supply of gas to both the main burner and the pilot burner in the event the pilot burner becomes extinguished for any reason before the supply of gas to both the main burner and the pilot burner is cut off by the main control valve.

Another object of the invention is to provide an oven burner ignition and control system of the character described wherein the pilot burner may be arranged to burn only when the main burner is turned on or to burn constantly if desired.

Still another object of the invention is to provide an improved electrical ignition and control system of the character described which may be used in conjunction with a time control mechanism or independently thereof as desired.

Other and more limited objects of the invention will be apparent from the following specification and the accompanying drawing forming a part thereof, wherein:

Fig. 1 is a diagrammatic view illustrating my improved electrical ignition and safety control mechanism as applied to a cooking range oven burner using gaseous fuel;

Fig. 2 is an enlarged central longitudinal vertical section through the safety control valve mechanism showing the various parts in the position they assume when the oven burner is turned off;

Fig. 3 is a view similar to Fig. 2 showing the various parts in the position they are automatically moved to when the main control valve is first turned on to initiate the operation of the main oven burner;

Fig. 4 is a wiring diagram showing the switches and the main control valve in off position;

Fig. 5 is a view similar to Fig. 4 showing the switches and the main control valve set for manual control of the main burner;

Fig. 6 is a view similar to Fig. 4 showing the

switches and main control valve set for automatic control of the main burner;

Fig. 7 is a view similar to Fig. 4 showing the switches and the main control valve set for the pilot burner to burn constantly;

Fig. 8 is a view similar to Fig. 4 showing a slightly different means for maintaining the pilot burner burning constantly; and

Fig. 9 is a detail section taken on the line 9—9 of Fig. 1.

Referring now to the drawings by reference characters, the numeral 1 indicates a gaseous fuel burner which is mounted in or in heating relation to a cooking range oven 2. Gaseous fuel is supplied to the burner 1 from a manifold M through a conduit 3. Interposed in the conduit 3 are a safety control valve mechanism generally indicated by the numeral 4, a manually operable main control valve 5, and an oven temperature control valve 6. The main control valve 5 is a plug valve of standard construction which when in open or on position permits the flow of gas through the conduit 3 from the manifold M to the burner 1, and in closed or off position cuts off flow of gas to the burner 1. This valve is manually opened and closed by a handle 7 and a valve stem 8, and directly controls the operation of the entire apparatus in that it initiates the operation of the entire apparatus when it is turned to an on position and terminates the operation when it is turned to the off position. From the manifold M gas flows through the conduit 3 to the safety control valve mechanism 4, to be described in detail hereinafter. From the safety control valve mechanism 4 the gas flows through the conduit 3, the main control valve 5, the oven temperature control valve 6 to the burner 1. The oven temperature control valve 6 is operative to regulate the amount of gas flowing to the burner 1 in order to maintain the oven at any desired set temperature. The valve 6 is set to any desired temperature by a handle 11 having a pointer 12 which cooperates with a graduated dial 13 carried by the valve 6. The valve 6 is controlled according to the temperature setting by a thermostatic element 14 which is mounted in the oven 2 and is connected to the valve 6 as shown at 15. The oven temperature control valve 6 is of standard well known construction. Consequently it is not shown in detail herein. There are many different constructions available any one of which will work equally well herein. Gas is also supplied to a pilot burner 16 through a branch conduit 17 which extends between the safety control valve mechanism 4 and the pilot burner 16. The pilot burner 16 is disposed adjacent the rear end of the main burner 1 in position to ignite the burner 1 when gas is supplied thereto. An electrical ignition element 18 is operatively associated with the pilot burner 16 in position to ignite the pilot burner 16 when gas is supplied thereto. A thermostatic element 19 and a multiple thermocouple 20 are mounted in position to be heated by a flame from the pilot burner. The thermostatic element 19 is operative to open and close a switch 21 which controls the energization of the electrical ignition element 18 and a solenoid 22 which when energized operates the safety control valve mechanism to supply gas to the pilot burner 16 as will be described in connection with the description of the safety control valve mechanism and the operation of the whole apparatus. The thermocouple 20 when heated is operative to hold the safety control valve mechanism in condition to main-

tain the supply of gas to both the pilot burner 16 and the main burner 1, as will also be described in connection with the description of the safety control valve mechanism and the operation of the apparatus. A master control switch 23 which is associated with the main control valve 5 is adapted to be opened and closed simultaneously with the closing and opening of the main control valve 5. As the control valve 5 is turned from the off or closed position to on or open position the master control switch 23 is moved from the open position to one closed position by the main control valve stem 8. Conversely, when the main control valve 5 is turned from open or on position to closed or off position the switch 23 is moved from closed position to open position.

An electric circuit between the thermocouple 20 and the safety control valve mechanism 5 is established by a copper tube 26 which encloses an insulated wire 27. The wire 27 is severed between the thermocouple 20 and the safety control mechanism 4 and an interrupter 28 having terminals 29 and 30 is interposed between the severed ends. One of the severed ends of the wire 27 is connected to the terminal 29 and the other severed end is connected to the terminal 30. The purpose and function of the interrupter 28 will be explained in detail in connection with the description of the operation of the apparatus.

The construction of the safety control valve mechanism 5 and its connection to the solenoid 22 will now be described, reference being had to Figs. 2, 3, and 4 of the drawing. This mechanism comprises a casing 35 having a chamber 36 in one end thereof and a chamber 37 in the other end thereof. The chambers 36 and 37 are connected by a bore 38 of reduced diameter. A valve seat 39 is located at one end of the bore 38 and a similar valve seat 40 is located at the other end of the bore 38. The chamber 36 is closed by a removable cap 41 and the chamber 37 is closed by a removable cap 42. A sleeve 43, having end walls 44 and 45, is carried by the cap 41 and extends into the chamber 36. A valve stem 46 which is slidably mounted in a bushing 47 carried by the end wall 45 of the sleeve 43, extends from the chamber 36 into the sleeve 43. A valve disc 48 of suitable material is secured to one end of the valve stem 46 within the chamber 36, and a metal disc 49 is secured to the other end of the stem 46 within the sleeve 43. A spring 50 disposed about the valve stem 46 between the valve disc 48 and the end wall 45 of the sleeve 43 normally holds the valve disc 48 against the valve seat 39. A horseshoe magnet 51 is secured to one end of a hollow exteriorly threaded stud 52 which extends out through aligned apertures in the end wall 44, of the sleeve 43, and in the end of the cap 41. A nut 53 screwed onto the outer portion of the stud 52 securely holds the magnet 51 and the sleeve 43 in place. The legs of the magnet 51 have a winding 54 thereon one end of which is connected to the tube 26 and the other end of which is connected to the wire 27 in the tube 26. The tube 26 is inserted into the hollow stud 52 and is held in place by a screw fitting 52a. A sleeve 55 is screwed into a threaded recess in the end of the cap 42, as indicated at 56, and extends into the chamber 37 a slight distance. One end of the sleeve 55 is closed by an end wall 57, and the other end which is open registers with a circular aperture 58 in the end wall of the cap 42. A plug 59 is slidably mounted in the sleeve 55 and extends out through the aperture 58 in the cap 42. A stem 62 which is secured to the inner end of the plug 59 extends out through an aper-

ture 63, in the end wall 57 of the sleeve 55, and through the chamber 37 and into the bore 38. The stem 62 has a collar 64 rigidly secured thereon between the end wall 57 and the outer end of the stem. A valve disc 65 of suitable material is slidably mounted upon the stem 62 between the end wall 57 of the sleeve 55 and the collar 64. The valve disc 65 is adapted to engage the valve seat 40 to cut off the flow of gas into the chamber 37 during the initiation of operation as will be hereinafter described. A compression spring 66 disposed about the stem 62 between the end wall 57 and the valve disc 65 normally yieldingly holds the valve disc 65 against the collar 64. A compression spring 67 which is stronger than the spring 66 is disposed about the stem 62 within the sleeve 55 between the inner face of the end wall 57 and the inner end of the plug 59. The spring 67 is operative to return the plug 59, stem 62 and valve disc 65 from the position shown in Fig. 3 back to their normal position as shown in Fig. 2, against the resistance of the spring 66. A port 68 in the casing 35 provides communication between the chamber 36 and the conduit 3 to allow gas to flow from the manifold M through the conduit 3 into the chamber 36. During normal operation of the main burner 1 gas flows from the chamber 36 through the reduced intermediate bore 38 and into the chamber 37. A port 69 which establishes communication between the conduit 17 and the bore 38 is provided to supply gas to the pilot burner 16; and a port 70 establishes communication between the chamber 37 and the conduit 3 to permit the flow of gas from the chamber 37 to the main burner 1 through the main control valve, and the oven temperature control valve.

The solenoid 22 may be connected to the safety control valve mechanism 4 in any desired suitable manner. As shown herein it is secured to the cap 42 of the safety control valve mechanism with armature thereof connected directly to the plunger 59 of the safety control valve mechanism.

The master control switch 23 which is mounted in a casing 25 secured to the main control valve 5 about the valve stem 8 comprises the arm 75 which is connected to the stem 8 of the manually operable main control valve 5 for rotation therewith, and the two contacts 76 and 77 which are spaced 180° apart and are adapted to be selectively engaged by the arm 75 when it is rotated 90° in either direction from its normal off position. The interrupter switch 24 which is also mounted in the casing 25 comprises the arm 78, which is connected to the valve stem 8 of the manually operable main control valve 5 for rotation therewith, and the two contacts 79 and 80 which are adapted to be selectively engaged by the arm 78. The contact 79 extends through an arc of 45° so that the arm 78 will engage the contact 79 upon 45° rotation of the valve stem 8 in a clockwise direction from the normal off position of the valve 5 and will remain in contact therewith during the next 45° rotation of the valve stem 8 in a clockwise direction. When the valve stem 8 is rotated in a counter-clockwise direction from the normal off position of the main control valve 5 the arm 78 will engage the contact 80 upon 90° rotation of the stem 8.

In order that the operation of the burner 1 may be automatically initiated at a predetermined set time and terminated at a predetermined set later time, we provide a supplemental master switch 82, a supplemental inter-

rupter switch 83 and a standard time control mechanism 84 which includes a self-starting electric clock 85 and is operative to open and close the supplemental switches 82 and 83 at predetermined set times. We also construct the manually actuated main control valve 5 so that it can be opened by turning the valve stem 8 through 90° in either direction from normal off position. For manual control the valve stem 8 is turned in a clockwise direction and for automatic control it is turned in a counter-clockwise direction. A finger 86 secured to the valve stem 8 is adapted to engage a stop 87 when valve 5 is set for manual control and a stop 88 when the valve is set for automatic control. A stationary dial 89 behind the valve handle 7 and a cooperating pointer 90 carried by the handle 7 indicate the setting of the valve 5.

The supplemental master switch 82 comprises the contacts 93 and 94 which are adapted to be bridged by a conductor bar 95; and the supplemental interrupter switch 83 comprises the contacts 97 and 98 which are adapted to be bridged by a conductor bar 99. The conductor bars 95 and 99 are adapted to be moved toward and away from the contacts 93, 94, 97 and 98 at predetermined times by the time control mechanism 84 through a connecting link 100.

The operation of the apparatus will now be described in connection with Figs. 4, 5 and 6. For manual control of the burner 1 the main control valve is opened by turning the valve stem 8 in a clockwise direction 90° by the handle 7, which moves the master control switch 23, the interrupter switch 24 and the main control valve 5 from their normal off positions as shown in Fig. 4 to the positions shown in Fig. 5 with the switch arm 75 engaging the contact 76 and the switch arm 78 engaging the contact 79. Current will now flow from one side 101 of the line through the lead 102, switch arm 75, contact 76 and lead 103 to the normally closed thermally opened switch 21. From the switch 21 the current flows through the lead 104 to the solenoid 22 and from there back to the other side 105 of the line through the lead 106. Current also flows from the switch 21 through the leads 104 and 107 to the electric ignition element 18 and from there back to the side 105 of the line through the leads 108 and 106. The solenoid 22 and the ignition element 18 are now energized. The solenoid 22 being energized shifts the various parts of the safety control valve mechanism from the positions shown in Fig. 2 to the position shown in Fig. 3. Gas can now flow to the pilot burner 16 where it is ignited by the ignition element 18, but it cannot yet flow to the main burner 1 since the valve mechanism in the chamber 37 of the safety control valve mechanism is maintaining the entrance thereto closed. The pilot burner 16 being ignited heats the thermocouple 20 and the thermal element 19. The thermocouple being heated generates a minute current of the order of 200 to 250 millivolts which flows from the thermocouple through the tube 26 to the winding 54 of the electromagnet 51 and from there through the wire 27 to the terminal 30 of the interrupter 28. From the terminal 30 the current flows through the lead 109, contact 79, switch arm 78 and lead 110 to the terminal 29 of the interrupter 28, and from there back to the thermocouple 20 through the wire 27. The thermocouple current energizes the electromagnet 51 sufficiently for it to hold the valve mechanism in the chamber 36 in the position shown in Fig. 3 after it has been moved to this position

by the solenoid 22, but not enough for the electromagnet to attract the mechanism from the position shown in Fig. 2 to the position shown in Fig. 3. The heating of the thermal element 19 causes it to open the normally closed switch 21 which breaks the circuit to and de-energizes the solenoid 22 and the ignition element 18. As soon as the solenoid 22 is de-energized the spring 61 returns the valve mechanism in the chamber 37 back from the position shown in Fig. 3 to the position shown in Fig. 2 while the electromagnet 51 holds the mechanism in the chamber 36 in the position shown in Fig. 3. Gas can now flow to the main burner 1 where it is ignited by the pilot burner 16. Under normal conditions the burner 1 will now operate under control of the oven temperature control valve 6 until its operation is terminated by the manual closing of the main control valve 5 which cuts off the supply of gas to the main burner 1 and returns the switches 23 and 24 to open position as shown in Fig. 4. The opening of the interrupter switch 24 breaks the thermocouple circuit and de-energizes the electromagnet 51 after which the spring 50 returns the mechanism in the chamber 36 from the position shown in Fig. 3 to the position shown in Fig. 2, thus cutting off the supply of gas to the pilot burner. If the pilot burner is extinguished for any reason during operation then the thermocouple 20 and the thermal element 19 will cool. The electromagnet 51 will then be de-energized and release the mechanism in the chamber 36 which will then be returned by the spring 50 to the position shown in Fig. 2 cutting off the supply of gas to both the pilot burner 16 and the main burner 1. When the thermal element 19 cools, which is after the thermocouple has cooled, the switch 21 will close. The apparatus will then recycle as described as soon as gas is available.

For automatic control of the burner 1 the main control valve 5 and the switches 23 and 24 are set as shown in Fig. 6 by turning the valve stem 8 counter-clockwise through 90° from the normal off position as shown in Fig. 4; and the time control mechanism 84 is set to close the supplemental switches 82 and 83 at the desired time and to reopen them at the desired later time. The switches 23 and 82 in the main circuit are now in series with each other, and the switches 24 and 83 in the thermocouple circuit are also in series with each other. When the time control mechanism 84 closes the supplemental switches 82 and 83 current will flow from the side 101 of the line through the lead 102, switch arm 75, contact 77, lead 114, switch 83 and leads 112 and 103 to the normally closed switch 21. From the switch 21 the current will flow through the solenoid 22 and the ignition element 18 and back to the other side 105 of the line. In the thermocouple circuit current will flow through the tube 28, winding 54 and wire 27 to the terminal 30. From the terminal 30 the current will flow through the leads 109 and 113, switch 83, lead 114, contact 80, switch arm 78 and lead 110 to the terminal 29 and from there through the wire 27 back to the thermocouple 20. The apparatus will now function as described in connection with manual control until the time control mechanism opens the switches 82 and 83 which breaks the main and the thermocouple circuits, thus terminating operation as previously described.

In order to operate the mechanism with a constantly burning pilot burner during a prolonged power failure, we set the switches 23 and 24 and

the main control valve 5 in off position as shown in Fig. 7 which is midway between the positions shown in Figs. 4 and 5. In this position the interrupter switch 24 is closed and the main control valve 5 is still closed. We then manually depress the plunger 59 to set the safety control valve mechanism as shown in Fig. 3 and light the pilot burner with a match. After the thermocouple has been heated by the pilot burner we release the plunger 59 allowing the mechanism in the chamber 37 of the safety control valve mechanism 4 to return to the position shown in Fig. 2 while the electromagnet 51 retains the mechanism in the chamber 36 in the position shown in Fig. 3. Gas will now be constantly supplied to the pilot burner but it cannot be supplied to the main burner until the main control valve 5 is opened by turning the valve stem 8 45° further in a clockwise direction. After the valve 5 has been opened gas will be supplied to the main burner and be ignited by the pilot burner. In order to prevent opening of the switch 24 by turning the valve stem 8 too far in a counter-clockwise direction when closing the valve 5 and thus extinguishing the pilot burner by breaking the thermocouple circuit, we provide a pivoted detent 115 which may be swung into position to be engaged by the finger 86, as shown in Fig. 9, and limit the movement of the valve stem 8 when closing the valve 5.

Another way of providing a constantly burning pilot light during a prolonged power failure is to interpose a manually operable switch 166 between the leads 109 and 110 of the thermocouple circuit as shown in Fig. 8. The switch 166 is independent of all the other switches in the apparatus and is closed only when a constantly burning pilot burner is desired. When the switch 166 is used the switch 24 is constructed as shown in Fig. 8 and the detent 115 is eliminated. Obviously the time control cannot be used during a power failure.

From the foregoing it will be apparent to those skilled in this art that we have provided a very simple and efficient mechanism for accomplishing the objects of the invention.

It is to be understood that we are not limited to the specific construction shown and described herein as various modifications may be made therein within the scope of the appended claims.

What is claimed is:

1. In an automatic ignition and control apparatus of the character described the combination of a main burner, a pilot burner operative to ignite said main burner, an electric ignition element operative when energized to ignite said pilot burner, a gaseous fuel supply manifold, a main conduit through which fuel is supplied to said main burner from said manifold, a manually operable control valve interposed in said conduit between said main burner and said manifold, a safety control valve mechanism operative to cut off the supply of fuel to said main burner and said pilot burner interposed in said conduit between said manually operable control valve and said manifold, a secondary conduit extending between said safety control valve mechanism and said pilot burner through which fuel is supplied to said pilot burner, a solenoid operatively connected to said safety control valve mechanism, said solenoid being operative upon energization to first set said safety control valve mechanism in condition to supply fuel to said pilot burner while cutting off the supply of fuel to said main burner and then upon subsequent de-energization to set said safety control valve mech-

anism in condition to also supply fuel to said main burner, an electromagnet associated with said safety control valve mechanism and operative when energized to maintain said safety control valve in said last set condition, a thermocouple adapted to be heated by said pilot burner, an electric circuit between said thermocouple and said electromagnet through whch said magnet is energized by said thermocouple when said thermocouple is heated, an interrupter switch interposed in said circuit and operative to open and close said circuit and thereby control the energization of said electromagnet, operative connections between said manually operable control valve and said interrupter switch through which said interrupter switch is closed and opened by the opening and closing of the manually operable control valve, a normally open master switch associated with said manually operable control valve, operative connections between said manually operable control valve and said master switch through which said master switch is closed by the opening of said main control valve and is opened by the closing of said main control valve, said master switch being operative when closed to energize said solenoid and said electric ignition element, a normally closed switch disposed in series with said master switch which is operative when opened to de-energize said solenoid and said electric ignition element, a thermostatic element adapted to be heated by said pilot burner and operative when heated to maintain said normally closed switch open and when cool to maintain said normally closed switch closed, and means operative to maintain said thermocouple circuit closed while said manually operable control valve is closed.

2. An automatic ignition and control apparatus as defined in claim 1 in which said means comprises a manually operable switch interposed in said thermocouple circuit in parallel with said interrupter switch and independent thereof.

3. An automatic ignition and control apparatus as defined in claim 1 in which said means is associated with said manually operable control valve and said interrupter switch and is operative to limit the closing movement of said manually operable control valve and the opening movement of said interrupter switch.

4. An automatic ignition and control apparatus as defined in claim 1 in which said means includes a detent operatively associated with said manually operable main control valve and said interrupter switch and which may be moved into and out of operative position and when in operative position limits the closing movement of said manually operable control valve and the opening movement of said interrupter switch.

5. In an automatic ignition and control apparatus of the character described the combination of a main burner, a pilot burner operative to ignite said main burner, an electric ignition element operative when energized to ignite said pilot burner, a gaseous fuel supply manifold, a main conduit through which fuel is supplied to said main burner from said manifold, a manually operable control valve interposed in said conduit between said main burner and said manifold, a safety control valve mechanism operative to cut off the supply of fuel to said main burner and said pilot burner interposed in said conduit between said manually operable control valve and said manifold, a secondary conduit extending between said safety control valve mechanism and said pilot burner through which fuel is supplied to said pilot burner, 75

a solenoid operatively connected to said safety control valve mechanism, said solenoid being operative upon energization to first set said safety control valve mechanism in condition to supply fuel to said pilot burner while cutting off the supply of fuel to said main burner and upon subsequent de-energization to set said safety control valve mechanism in condition to also supply fuel to said main burner, an electromagnet associated with said safety control valve mechanism and operative when energized to maintain said safety control valve in said last set condition, a thermocouple adapted to be heated by said pilot burner, an electric circuit between said thermocouple and said electromagnet through which said magnet is energized by said thermocouple when said thermocouple is heated, an interrupter switch having two closed positions interposed in said circuit and operative to open and close said circuit and thereby control the energization of said electromagnet, operative connections between said manually operable control valve and said interrupter switch through which said interrupter switch is closed and opened by the opening and closing of the manually operable control valve, a normally open master switch having two closed positions associated with said manually operable control valve, operative connections between said manually operable control valve and said master switch through which said master switch is closed by the opening of said main control valve and is opened by the closing of said main control valve, said master switch being operative when closed to energize said solenoid and said electric ignition element, a normally closed switch disposed in series with said master switch which is operative when opened to deenergize said solenoid and said electric ignition element, a thermostatic element adapted to be heated by said pilot burner and operative when heated to maintain said normally closed switch open and when cool to maintain said normally closed switch closed, a supplemental master switch disposed in series with said master switch and said normally closed switch when said master switch is in one of its closed positions, a supplemental interrupter switch interposed in said circuit in series with said interrupter switch when said interrupter switch is in one of its closed positions, and a time control mechanism operative to simultaneously close and open said supplemental master switch and said supplemental interrupter switch at predetermined set times.

6. In an automatic ignition and control apparatus of the character described the combination of a main burner, a pilot burner operative to ignite said main burner, an electric ignition element operative when energized to ignite said pilot burner, a gaseous fuel supply manifold, a main conduit through which fuel is supplied to said main burner from said manifold, a manually operable control valve interposed in said conduit between said main burner and said manifold, a safety control valve mechanism operative to cut off the supply of fuel to said main burner and said pilot burner interposed in said conduit between said manually operable control valve and said manifold, a secondary conduit extending between said safety control valve mechanism and said pilot burner through which fuel is supplied to said pilot burner, a solenoid operatively connected to said safety control valve mechanism, said solenoid being operative upon energization to first set said safety control valve mechanism in condition to supply fuel to said

pilot burner while cutting off the supply of fuel to said main burner and then upon subsequent de-energization to set said safety control valve mechanism in condition to also supply fuel to said main burner, an electromagnet associated with said safety control valve mechanism and operative when energized to maintain said safety control valve in said last set condition, a thermocouple adapted to be heated by said pilot burner, an electric circuit between said thermocouple and said electromagnet through which said magnet is energized by said thermocouple when said thermocouple is heated, an interrupter switch interposed in said circuit and operative to open and close said circuit and thereby control the energization of said electromagnet, operative connections between said manually operable control valve and said interrupter switch through which said interrupter switch is closed and opened by the opening and closing of the manually operable control valve, a normally open master switch associated with said manually operable control valve, operative connections between said manually operable control valve and said master switch through which said master switch is closed by the opening of said main control valve and is opened by the closing of said main control valve, said master switch being operative when closed to energize said solenoid and said electric ignition element, a normally closed switch disposed in series with said master switch which is operative when opened to de-energize said solenoid and said electric ignition element, means responsive to said pilot burner and operative to maintain said normally closed switch open while said pilot burner is ignited, and means operative to maintain said thermocouple circuit closed while said manually operable control valve is closed.

7. An automatic ignition and control apparatus as defined in claim 6 in which said means comprises a manually operable switch interposed in said thermocouple circuit in parallel with said interrupter switch and independent thereof.

8. An automatic ignition and control apparatus as defined in claim 6 in which said means is associated with said manually operable control valve and said interrupter switch and is operative to limit the closing movement of said manually operable control valve and the opening movement of said interrupter switch.

9. An automatic ignition and control apparatus as defined in claim 6 in which said means includes a detent operatively associated with said manually operable main control valve and said interrupter switch and which may be moved into and out of operative position and when in operative position limits the closing movement of said manually operable control valve and the opening movement of said interrupter switch.

10. In an automatic ignition and control apparatus of the character described the combination of a main burner, a pilot burner operable to ignite said main burner, an electric ignition element operative when energized to ignite said pilot burner, a gaseous fuel supply manifold, a main conduit through which fuel is supplied to said main burner from said manifold, a manually operable control valve interposed in said conduit between said main burner and said manifold, a safety control valve mechanism operative to cut off the supply of fuel to said main burner and said pilot burner interposed in said

conduit between said manually operable control valve and said manifold, a secondary conduit extending between said safety control valve mechanism and said pilot burner through which fuel is supplied to said pilot burner, a solenoid operatively connected to said safety control valve mechanism, said solenoid being operative upon energization to first set said safety control valve mechanism in condition to supply fuel to said pilot burner while cutting off the supply of fuel to said main burner and upon subsequent de-energization to set said safety control valve mechanism in condition to also supply fuel to said main burner, an electromagnet associated with said safety control valve mechanism and operative when energized to maintain said safety control valve in said last set condition, a thermocouple adapted to be heated by said pilot burner, an electric circuit between said thermocouple and said electromagnet through which said magnet is energized by said thermocouple when said thermocouple is heated, an interrupter switch having two closed positions interposed in said circuit and operative to open and close said circuit and thereby control the energization of said electromagnet, operative connections between said manually operable control valve and said interrupter switch through which said interrupter switch is closed and opened by the opening and closing of the manually operable control valve, a normally open master switch having two closed positions associated with said manually operable control valve, operative connections between said manually operable control valve and said master switch through which said master switch is closed by the opening in said main control valve and is opened by the closing of said main control valve, said master switch being operative when closed to energize said solenoid and said electric ignition element, a normally closed switch disposed in series with said master switch which is operative when opened to de-energize said solenoid and said electric ignition element, means responsive to said pilot burner and operative to maintain said normally closed switch open while said pilot burner is ignited, a supplemental master switch disposed in series with said master switch and said normally closed switch when said master switch is in one of its closed positions, a supplemental interrupter switch interposed in said circuit in series with said interrupter switch when said interrupter switch is in one of its closed positions, and a time control mechanism operative to simultaneously close and open said supplemental master switch and said supplemental interrupter switch at predetermined set times.
